(57) **CLAIM**

The ornamental design for a counterweight for a wheeled loading shovel vehicle, as shown and described.

DESCRIPTION

FIG. 1 is a front, right side, and top perspective view of a counterweight for a wheeled loading shovel vehicle showing our new design.

FIG. 2 is a top plan view thereof.

FIG. 3 is a front elevation view thereof.

FIG. 4 is an enlarged left side elevation view thereof.

FIG. 5 is an enlarged right side elevation view thereof.

FIG. 6 is a bottom plan view thereof.

FIG. 7 is a back elevation view thereof.

FIG. 8 is a front, left side, and top perspective view thereof.

FIG. 9 is a back, right side, and top perspective view thereof; and,

FIG. 10 is a back, left side, and top perspective view thereof.
